UNITED STATES PATENT OFFICE.

WILLIAM N. FURTHMANN, OF CHICAGO, ILLINOIS, ASSIGNOR TO GRAY-HEATH COMPANY, OF CHICAGO, ILLINOIS, A CORPORATION OF ILLINOIS.

ATTACHMENT-PLUG FOR ELECTRIC HEATING DEVICES.

1,329,592.

Specification of Letters Patent.

Patented Feb. 3, 1920.

Application filed April 19, 1919. Serial No. 291,370.

To all whom it may concern:

Be it known that I, WILLIAM N. FURTHMANN, a citizen of the United States, residing at Chicago, in the county of Cook and State of Illinois, have invented certain new and useful Improvements in Attachment-Plugs for Electric Heating Devices, of which the following is a specification.

Electric heating devices, such as toasters, 10 sad-irons, and the like, are commonly equipped with contact terminals in the form of a pair of fingers or prongs, which enter sockets in a removable attachment plug on the end of the circuit wire, the sockets of the 15 attachment plug carrying expansible metal contacts coöperating with the contact prongs or fingers of the heating device to close the circuit.

In the manufacture of such heating devices there is at present no standardization 20 of the contact devices. In some cases the prongs take the form of relatively thin, flat blades, in other cases the prongs are substantially square in cross section. In still other 25 cases the prongs are of an oblong rectangular form in cross section, and in still other instances they are substantially circular in cross section. As a result of this, it has heretofore been necessary to provide different 30 styles of attachment plug, each carrying expansible contact strips adapted to the particular form of the prongs or fingers of the heating device.

The principal object of the present invention 35 is to provide an attachment plug of such a construction that it shall be adaptable to and usable with any and all of the different forms of contact prongs or fingers found on the various heating devices in use; and 40 this object I accomplish chiefly through the employment of hollow expansible contact members carried by the attachment plug which are of substantially diamond form in cross section, and divided on the line of the 45 major axis.

My invention, its manner of use, and its 50 practically universal adaptability to the different forms of prongs or fingers will be readily understood and appreciated by those skilled in the art by reference to the accompanying drawing, in which—

Figure 1 is a top plan view of the lower half of the body of the plug showing the hollow metallic contact pieces seated therein.

Fig. 2 is an end view of the attachment 55 plug, as seen from the right of Fig. 1.

Fig. 3 is a cross-sectional view.

Fig. 4 is a perspective detail of one of the 60 hollow longitudinally split contact pieces carried by the plug; and

Figs. 5, 6, 7 and 8 are detail sectional views illustrating the adaptability of the device for coöperation with contact prongs or fingers of various cross-sectional forms.

Referring to the drawing, 9 and 10 designate 65 the upper and lower mating halves of the body of the plug, which is made of any suitable insulating material, these halves being united by bolts 11. In the inner opposed faces of the body members 9 and 10 70 are formed depressions or seats 12 and 13 which, when the parts are united, form a pair of parallel sockets each of substantially diamond form in cross-section. Directly in 75 the rear of the sockets 12 and 13 are rectangular sockets 14 which accommodate the inner ends or shanks of the longitudinally split contact pieces hereinafter described, and at the left hand end, as shown in Fig. 1, is a forked duct or passageway 15 to accommodate 80 circuit wires 16.

Housed within the diamond-shaped sockets 85 are the metallic contact pieces, each of which comprises a hollow metallic member 17 of substantially diamond form in cross-section and longitudinally split preferably in the plane of the major axis of its cross section, so as to be expansible transversely within the limits permitted by the socket itself which is of somewhat greater cross 90 section than the contact piece itself. At the inner end of each contact piece is a flat shank 18 of double thickness, through which is passed the binding screw 19 for the circuit wire 16. Preferably, and as shown in 95 Fig. 4, each contact piece is formed of a pair of mating sections united through their stems or shanks 18 by the binding screws 19, the material used being phosphor-bronze, brass, or some other conducting material 100 having a springy or elastic quality.

Figs. 5 to 8, inclusive, illustrate the adaptability of these hollow contact pieces to receive contact prongs or fingers of varying sizes and cross sectional forms. Fig. 5 illustrates 105 the use of the device with a contact finger or blade 20 of relatively wide and thin form. Fig. 6 illustrates its use with

a contact finger 21 of substantially square form in cross section. Fig. 7 illustrates its use with a contact finger of oblong rectangular form; and Fig. 8 illustrates its use 5 with a contact finger 23 of circular form in cross section. It will be observed that with each of these different forms of contact fingers a plurality of line contacts are secured, the elastic jaws of the contact piece springing apart slightly when the contact finger is 10 inserted, and thereby securing a strong frictional contact.

I claim:

1. An electrical attachment plug, comprising a body member of insulating material having a pair of contact-holding sockets in one end thereof, and contact pieces housed in said sockets and each comprising a hollow metallic member of substantially 15 diamond shape in cross-section and split longitudinally in the plane of the major axis of its cross-section.
2. An electrical attachment plug, comprising a body member of insulating mate-

rial having a pair of contact-holding sockets 25 in one end thereof, and contact pieces housed in said sockets and each comprising a pair of spring jaws each of semi-diamond shape in cross-section lying face to face, said jaws at their inner ends having flat 30 stems or shanks united by a binding screw.

3. An electrical attachment plug, comprising a body member made in mating halves, said halves having formed in their meeting faces parallel recesses of semi-diamond form in cross-section, and the recesses of the two halves when brought into register forming contact-holding sockets of diamond form in cross-section, contact pieces housed in said sockets and each comprising a pair 40 of spring jaws each of semi-diamond form in cross-section lying face to face, said jaws being of less cross-sectional dimensions than said sockets, and said jaws at their inner ends having flat integral stems or shanks 45 united by a binding screw, and means for uniting the halves of said body member.

WILLIAM N. FURTHMANN.
